(57) **CLAIM**

The ornamental design for a car, toy replica and/or other replica, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a car, toy replica and/or other replica showing my new design;

FIG. 2 is a left side elevational view thereof;

FIG. 3 is a front and left side perspective view thereof;

FIG. 4 is a rear elevational view thereof;

FIG. 5 is a front elevational view thereof;

FIG. 6 is a rear and left side perspective view thereof; and;

FIG. 7 is a right side elevational view thereof.

The broken lines in the figures illustrate portions of the car that form no part of the claimed design.
